[57] CLAIM

The ornamental design for a fluorescent light fixture, as shown and described.

DESCRIPTION

FIG. 1 is a top perspective view of an externally switched

embodiment of the fluorescent light fixture showing my new design;

FIG. 2 is a bottom perspective view thereof;

FIG. 3 is a side view thereof;

FIG. 4 is a bottom view thereof;

FIG. 5 is a top view thereof;

FIG. 6 is a side view rotated 90 degrees from the side view of FIG. 3;

FIG. 7 is a bottom perspective view of the internally switched embodiment of the fluorescent light fixture showing my new design;

FIG. 8 is a side view of the internally switched embodiment of FIG. 7.

The broken lines in FIG. 1 are shown for illustrative purposes only and form no part of the claimed design.

The second embodiment as disclosed in FIGS. 7 and 8 differ from the first embodiment only by the addition of the switch.
